UNITED STATES PATENT OFFICE.

HARRY ELDRED TAYLOR, OF PARIS, FRANCE.

IGNITION DEVICE FOR INTERNAL-COMBUSTION ENGINES.

Application filed November 8, 1921, Serial No. 513,766. Renewed August 28, 1924.

To all whom it may concern:

Be it known that I, HARRY ELDRED TAYLOR, a citizen of the United States, residing at Paris, in the Republic of France, have invented new and useful Improvements in Ignition Devices for Internal-Combustion Engines, of which the following is a specification.

My invention relates to improvements in ignition devices with induction coil for internal combustion engines, whereof the principal advantage consists in producing a spark within each cylinder of the engine not only at the end of the compression stroke as in known devices but also during the exhaust stroke, thereby obtaining the complete combustion of the gas within the cylinders.

Another advantage resides in the fact that the various mechanical parts are disposed upon a common frame or base adapted to be secured to or removed from the engine with great facility. Furthermore, the construction of the apparatus is of a very simple character and provides for the perfect insulation of the electric conductors.

The following description together with the accompanying drawings which are given by way of example sets forth an embodiment of my invention, wherein:

Fig. 1 is a longitudinal section of the device.

Fig. 2 is a partial longitudinal section approximately on the line A—A, Fig. 1.

Fig. 3 is a front view of a detail of the actuating device of the cam of the make and break device.

Fig. 4 is a diagrammatic cross-section of the high tension distributor approximately on the line B—B, Fig. 2.

The apparatus herein represented comprises a main frame of cast aluminium 50 having formed in the rear side thereof a recess 51 adapted to receive a projection of one of the engine parts whereby the frame 50 shall be maintained exactly in the desired position. The frame 50 has formed therein an inclined aperture 52 which receives a bolt 53 serving to secure the said frame to the cover of timing gears of the engine, for instance a Ford engine. The said bolt may also serve in the case of this latter engine to regulate the tension of the belt of the air fan.

The lower part of the frame 50 is provided with an aperture having disposed therein the cam shaft 54 of the engine where-

upon is rotatably mounted the pinion 55. The shaft 54 has keyed thereon a sleeve 56 having pivoted thereto two arms 57 constituting a centrifugal governor. The said arms 57 are connected by the links 58 to a cam 59 centered upon the shaft 54 and provided with eight bosses cooperating with a fibre pin 61 secured to the semicircular lever 62 of the interrupter device. The said lever 62 is pivoted to a screw 63 for grounding the same, and is brought back by a spring 64. The lever 62 is provided with a tungsten point 66 cooperating with a stationary insulated contact stud 67. The frame 50 has formed at the top part a hollow cylindrical portion constituting a casing 50' for containing the spark coil 68.

The contact stud 67 is connected by a wire 69 to a contact stud 70 disposed in the bottom of the casing 50'. The wire 69 is contained within a porcelain tube 71 which is surrounded by the metal of the frame 50, thereby affording a perfect insulation and obviating all visible wires.

The spark coil 68 comprises the soft iron core 73 and the primary winding 74 connected with a condenser and with a spring contact plug 76 cooperating with the contact stud 70 when the said spark coil is disposed within the casing 50'. The other end of the primary winding is connected with the spring contact plug 77 cooperating with a stud 78 disposed upon a casing 79 of insulating material. The latter is secured to the cover 80 of the casing 50' by a nut 79'. The stud 78 is connected with a wire 81 having a suitable resistance and wound in a suitable number of turns about a metal tube or rod 82 which is secured at 83 to the receptacle 79. The end of the wire 81 is connected with a small automatic switch constituted by a bell-crank lever 84, or the like, whose vertical arm is adapted to be driven back by the tube 82 when this latter is caused to expand by the action of the heat produced by the current in the wire 81. The other arm of the said lever is normally in contact with an insulated stud 86 disposed in the cover 79 and connected with a binding post 88. The latter may be connected with one of the poles of the battery or low tension magneto supplying the primary current.

The other pole of the said source of current is connected with a second binding post 87 connected to a contact stud 92 cooperat-

ing with the spring contact plug 93 disposed upon the spark coil. The contact 93 has connected thereto one end of the high tension winding 94 as well as one side of the condenser 75. It is grounded to the part 50' for instance by a lateral stud 90.

The other end of the high tension winding is connected with a spring contact plug 95 when the said spark coil is inserted in 10 the casing 50'; the latter plug is thereby connected through the intermediary of the stud 70' with a wire 96 which is also contained in a porcelain tube 97 surrounded by the aluminium frame 50. The wire 96 ends 15 in a contact stud 98 cooperating with a stud 99 provided upon the rotary contact disk 100; the latter has disposed thereon the driving pinion 101 and is mounted on a ball bearing 102.

20 In the example herein represented which is applicable to a four-cylinder engine, the rotary contact device comprises suitable conductors connecting the stud 99 with a tungsten point 103 disposed on the surface of the 25 said disk and with a second tungsten point 104 disposed on the periphery of the disk and diametrically opposite the former. The stud 99 is also connected with a like metal point 105 constituting a lightning arrester 30 together with a stud 106 secured to and grounded upon the machine (pinion 101). The metal point 103 cooperates with four tungsten inserts 1°, 2°, 3°, 4° disposed on the 35 internal wall of the high tension distributor 107, of the said rotary contact device. The metal point 104 cooperates with four like inserts 1°, 2°, 3°, 4° disposed on the internal periphery of the said distributor plate. The eight studs are connected in pairs with four 40 contact members 108 mounted in said distributor plate as shown in Fig. 4 and respectively connected with the spark plugs by pressure button contacts 108' in a known manner.

45 The pinion 101 of the rotary contact device is actuated by the gear wheel 55 through the medium of the pinion 110 which is mounted on ball bearings within the frame 50.

50 The cover 80 of the casing 50' is maintained by the fastening device 111 which is for instance of the combination lock-type. The owner of the vehicle is thus enabled to remove the spark coil with facility in order 55 to prevent theft of the vehicle.

The said apparatus operates in the following manner:

50 The primary current having been brought to the binding posts 87, 88 and the cam shaft 60 being actuated, should one of bosses of the cam 59 encounter the pin 61, the movable contact piece 66 will become separated from stationary contact piece 67. The break of the primary circuit thus ensuing will give 65 rise to a secondary current which is sent by

the rotary device 101 for instance to the metal point 104 cooperating with the metal stud 1°. The apparatus is so adjusted that the spark thus produced takes place in the first cylinder at the end of the compression stroke, for instance 45% of the crank shaft before dead center. It will be observed that the points 103, 104 do not enter in friction contact with the metal inserts of the distributor, but the current passes in the form of a jump spark between each point and the corresponding inserts. This will have the effect of increasing the intensity of the spark at the spark plugs and will also reduce the wear and obviate the bad contacts resulting from the use of carbon brushes.

70 At the end of a quarter of a revolution, or approximately, of the cam shaft 54, another break of the primary current will be produced at this moment the metal point 103 comes opposite the inserts 3° and the current is caused to pass into the spark plug in the third cylinder which is now in the exhaust stroke. Shortly after a fresh break will take place and the point 104 will cooperate with the insert 2°, thereby sending the current to the spark plug of the second cylinder which is now acting at the end of the compression stroke and so on. The explosions have for 75 instance the following sequence: 1°, 3°, 2°, 1°, 80 4°, 2°, 3°, 4°.

85 Inasmuch as the spark is thus produced in each cylinder during the exhaust stroke, the gas which is not burnt and which remains in the cylinder may be thus consumed as well as the oil which is projected by the piston during the exhaust stroke, at the same time obviating all explosions in the muffler box and the damage resulting therefrom, and likewise the fouling of the spark plugs.

90 The driving relation between the driving member 56 and the pinions 55 and 101 is determined by the position of the weights 57. As the speed increases the weights move outwards because of the centrifugal force, the gears are displaced angularly to the driving plate 56 and the spark time is 95 thereby advanced.

100 It will be observed that the two contact members 78 and 92 are so disposed that by turning the casing 79 and thereby reversing said contacts, the direction of the current may be reversed thereby reducing the wear of the tungsten points of the device and the electrodes of the spark plugs.

105 In case the primary current is supplied by a battery, should the driver fail to switch off the current when the engine is not running, the said current by passing through the wire 81 and heating the tube 82', the latter will thereupon expand and will act upon the bell-crank lever 84 thus automatically cutting off the current.

110 It is obvious that my said invention is 115 not limited to the details of construction as 120

hereinbefore set forth, the same being given solely by way of example. A suitable plate may be supplied with the device when employed on an engine other than the Ford 5 type, whereby the said device may be secured with facility to the engine base plate adapted for a magneto or the end plate of a dynamo.

Having now described my invention, what 10 I claim as new and desire to secure by Letters Patent is:

1. An ignition device for internal combustion engine embodying a single metal frame having formed therein a recess by 15 means of which it is liable to be secured on a corresponding protruding portion of the engine and a hollow part which forms a casing, an induction coil removably mounted in said casing, an interrupter for the primary current and a rotary distributer for the secondary current mounted on said frame, and electric connections between the induction coil on the one hand and the in-

terrupter and the distributer on the other hand.

2. An ignition device for internal combustion engine embodying a single metal frame having formed therein a recess by means of which it is liable to be secured on a corresponding protruding portion of the engine and a hollow part which forms a casing, an induction coil removably mounted in said casing, an interrupter for the primary current and a rotary distributer for the secondary current mounted on said frame, and electric connections between the induction coil on the one hand and the in- 25

terrupter and the distributer on the other hand, said electric connections embodying electric conductors inserted in porcelain tubes which are embedded in the said metal frame.

In testimony whereof I have signed my name to this specification.

HARRY ELDRED TAYLOR.
